CLAIM

The ornamental design for a scissors, as shown and described.

DESCRIPTION

FIG. 1 is a perspective view of the scissors showing my new design;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a sectional view taken along line 6—6 of FIG. 2.

The broken line illustration of the blade and its attachment to the scissors is for illustrative purposes only and forms no part of the claimed design.

FIG. 1.

FIG. 2.

FIG. 3.

FIG. 5.

FIG. 4.

FIG. 6.
